UNITED STATES PATENT OFFICE.

LARS H. VOLD AND KARL R. HAMMERSTROM, OF BUTLER, PENNSYLVANIA.

AIR-CONTROL MECHANISM FOR PUNCHING MACHINES.

Application filed November 4, 1926. Serial No. 146,192.

This invention relates to improvements in automatic multiple spacing-punches, more particularly to improvements in the multiple punch shown and described in an earlier Patent No. 833,811, issued October 23, 1906, to Lars H. Vold, one of the co-inventors of the present invention.

The patent referred to covers a multiple punch in which the work is automatically moved to certain desired intervals of space and also means for controlling a series of gag-blocks cooperating with punches to render the desired punch or punches operative in acting upon the work. The automatic regulation of moving the work and controlling the gag-blocks is obtained by pneumatic actions controlled by or responsive to a perforated paper sheet that is fed through the machine. The punch action is produced by a cam actuated lever acting upon a punch bar and the movement of the paper sheet in passing through the machine for automatically spacing the work and controlling the gags is regulated by a separate cam designed to coordinate the function of feeding the paper through the machine with the operating cycle of the punch bar.

The cam operated punch has in recent years been superseded by the eccentric type which imparts a uniform reciprocatory movement to the punch bar, and it is an object of the present invention to adapt the pneumatic actions for spacing the work and controlling the punch gags to the eccentric type of punch.

Another object of the invention is to provide separate and independent means for controlling the work, advancing or spacing mechanism and the control mechanism of a series of punch gags to render said mechanisms severally operative during a predetermined period of the operating cycle of the punch bar member.

Another object of the invention is to provide the longest possible time for the operation of the punch gag control mechanism and the shortest possible time for the operation of the work spacing mechanism to eliminate interference of the control mechanism with the movable elements of the machine with which they cooperate.

Another object of the invention is to design the control mechanism referred to above to adapt it to eccentrically operated punch bars without necessitating any substantial changes

in the machine disclosed in the aforementioned patent.

In the accompanying drawings constituting a part hereof and in which like reference characters designate like parts, Fig. 1 is a diagrammatic view of a portion of an automatic multiple punch embodying the principles of this invention; Fig. 2 is a side elevational view of an improved paper tower; Figs. 3, 4 and 5 are views in elevation of portions of the paper tower mechanism; Fig. 6 is a cross sectional view partially in elevation of the paper tower taken along the lines VI—VI, of Fig. 2; Fig. 7 is an end elevational view of the paper tower shown in Fig. 2; Fig. 8 is a sectional view of a pair of air boxes cooperating with the paper tower mechanism; and Figs. 9, 10, 11, 12 and 13 are diagrams graphically illustrating the relative functions of the cam actuated punch bar and the eccentrically operated punch bar with their respective paper tower mechanisms to aid in the description and understanding of the present invention. To aid in the description of the invention, only so much of the punch has been illustrated as is necessary for a full understanding of the improvements herein described and claimed.

Referring to Fig. 1 the reference numeral 1 designates a punch bar connected to an eccentric by means of a link 2 and provided with a plurality of punch-holders 3 for carrying punches 4, the punch holders being adjustably secured to the reciprocating punch bar 1. The punch holders are respectively provided with cylinders 5 carrying pistons 6 having gag-blocks 7 secured to one end thereof which cooperate with the stems of the punches 4 to lock them in their sockets when a source of pressure such as compressed air is applied to the ends of the cylinders 5 as by means of tubes 8 communicating by pipe lines 9 with a pair of air boxes 10 of the paper tower. When the air pressure is cut off from the cylinders 5 the latter are automatically exhausted to the atmosphere, in a manner hereinafter described, so that the gag-blocks 7 are withdrawn from the punches 4 by action of springs 4^a leaving the punches free to move vertically in their sockets without any restraint upon the operation of the punch bar 1.

The punches 4 cooperate with a series of dies 11 secured to a punch block 12 mounted

on the base of the machine frame and the work 13 passing between the dies and punches, comprising sheet metal or the like, is mounted on a carrier 14 provided with a gripper 15 which secures the edge of the sheet 13 and draws it over the dies in accordance with the movement of the carrier 14 which movement is produced by a ratchet-actuated spacing mechanism that is fully described in the 10 aforementioned patent and in our copending application Serial No. 113,152 filed June 2, 1926. The carrier 14 is provided on its underside with rack teeth 16 cooperating with a gear wheel 17 mounted on the feed shaft 18 upon which ratchet wheels 19 and bevel gears, not shown, are mounted.

The feed shaft 18 is actuated by ratchet pawls 20 for intermittently advancing the work carrier 14 in accordance with the action 20 of the punch bar 1, the pawls 20 being carried by a swing frame 21 that is connected by a link 22 to a block 23. The block 23 is movably mounted in a curved guideway 24 of a rocker frame 25 which is supported by an arm 25^a and is pivotally connected at 26 to a link 27 pivoted at 28 to a crank pin carried by cam 46 mounted on shaft 29. The shaft 29 is rotated through a bevel gear connection 30 with a connecting shaft 31 that is actuated by the eccentric drive shaft 32 of the punch bar, the gear ratio being maintained at one-to-one to provide the same speed of rotation of the shaft 29 to that of the eccentric shaft 32.

The block 23 of the rocker frame 25 is further connected by a link 33 to a slide bar 34 having an offset portion 35 which engages a pair of jaws 36 and 37 of a pair of floating tongs 38 and 39 respectively. The movement of the member 35 is limited to the space between the jaws 36 and 37 and this movement determines the position of the block 23 in the slot 24 which controls the swinging movement of the ratchet actuating frame 21. The movement of the jaws is regulated by the separating or closing of the tongs 38 and 39 which cooperate by virtue of a link connection 40 and the tongs are actuated by virtue of the connection of the tong 38 through a link 41 to the lower portion of the swing frame 25. The closing position of the jaws 36 and 37 is regulated by a plurality of spacing pins 42 shown in dotted lines which are independently actuated by air pressure from the paper tower, generally designated at 43, to be forced 55 downwardly in the path of movement of the jaws, the particular spacing pin forced down by the paper tower determining the closing position of the jaws 36 and 37 and incidentally fixing the position of the block 23. As shown in Fig. 8, spacing pins 42 are enlarged at one end to form a piston which moves in a cylinder formed in the jaw guide block, and a spring 42^a normally retains the pin in retracted or inoperative position. When air 60 is supplied through pipes 52 by the action of

the paper tower, in a manner to be hereinafter described, pins 42 are forced down to limit the movement of jaws 36 and 37. A plurality of these pins are provided to give all the necessary combinations of jaw travel. 70

The spacing pins 42, control the distance or space intervals at which the work 13 is advanced through the machine, and the gag-blocks 7 are rendered operative through the paper tower 43 which is regulated in its operation by a follower 45 cooperating with the paper tower cam 46 carried by the shaft 29, the follower 45 being connected through the lever 47 and the link 48 to a bell crank 49 which is associated with the paper tower in 80 a manner as will be hereinafter explained.

The gag blocks and spacing pins 7 and 42, respectively, are operated by air pressure leading from the paper tower 43, Fig. 6, which comprises a stationary cylinder 50 having a plurality of orifices 51 communicating through pipes 52 with the air boxes 10 and air pins 42, Figs. 1 and 8. The stationary cylinder is of semi-cylindrical shape to provide a contacting surface for a paper sheet 53 which is unreeled from a drum 54 and wound on a drum 55, the drum 55 being frictionally connected by a gear train 56, Fig. 2, to shaft 59. The sheet 53 is provided with perforations that register with projections 57, Fig. 7, of a pair of guide wheels 58 for the purpose of providing proper alignment of the recorded perforations in the paper with the orifices 51 of the stationary cylinder. The spacing or guide wheels 58 are mounted on the shaft 59 which has a ratchet wheel 60 secured thereto and is adapted to rotate therewith, the ratchet wheel being actuated by a pawl 61 that is pivoted at 62 to a lever 63 which is movable between a pair of 100 adjustable stops 64 and 65 for the purpose of limiting the throw of the pawl 61 which determines the rotative movement of the ratchet wheel 60 and consequently the movement of the paper sheet 53 over the stationary cylinder 50. The pawl 61 is connected by a link 66 to the arm 67 of a bell crank 49 which is connected by the link 48 to the cam follower 45 of the paper tower cam 46, Fig. 1. The link 66 is connected to the arm 67 of the bell crank 49 by engagement of the latter between a collar 68, spaced on the link 66 by a spring 69 and nut 70 secured to the end of the link 66. Another arm 71 of the bell crank 49 is secured by a pin 72 in a slot 73 of a link 110 74 that is provided with a notched portion 75 for engaging trunnions 76 of a hand lever 77. The link 74 is provided with a collar or washer 78 that rests upon a segmental guide 79 projecting from the paper tower and is frictionally engaged by pressure exerted by a coil spring 80, Fig. 7. The link 74 may be pulled out of contact with the trunnions 76 of the lever 77 and permit the latter to be raised about its pivot 81. The lever 77 is 115 120 125 130

provided with adjustable stops 82 and 82^a that cooperate respectively with valve stems 83 and 84, Figs. 2 and 6, of valves 85 and 86 connected to a source of pressure such as compressed air which is conducted to the valves through the pipe 87, Fig. 7.

Referring to Figs. 3, 4 and 5, valves 85 and 86 are disposed in a pressure bar 88, which is formed with an arm 91^a and provided with a plurality of orifices 89 and 90, these latter being grouped into fields, as shown in Fig. 5. Arm 91^a is provided with a longitudinal bore 110 which extends from a hollow shaft 111 to valve 85, and another passage 112 extends from that valve to valve 86. Fluid pressure, such as compressed air, is supplied to the valves through a pipe 87 connected to hollow shaft 111. When valves 85 and 86 are opened air is supplied to orifice field 90 through a duct 91 connected to valve 85, and to field 89 through a duct 92 connected to valve 86, ducts 91 and 92 not being in communication with one another. Valve 85 and orifice field 90 control gag blocks 7, and valve 86 with field 89 controls air pins 42. Downward movement of lever 77 about its pivot 81 will open valves 85 and 86 through contact of stops 82 and 82^a with valve stems 83 and 84, respectively. These stops may be adjusted to open the valves in any predetermined relation. In the preferred practice of the invention, the stops are adjusted to open valve 85 first, and valve 86 is not opened until lever 77 has moved to a lower position. Thus separate and adjustable control of the gag blocks and air pins is provided. The groups or fields of orifices 89 and 90 of the air clamp bar 88 are adapted to register with orifices 51 of the stationary paper tower cylinder 50 as shown in Fig. 6, the paper sheet 53 passing therebetween, so that when communication is established between the source of pressure leading to the respective fields 89 and 90 the orifices in the paper sheet 53 corresponding with any of the orifices in the groups 89 and 90 will permit the passage of air therethrough into the orifices 51 of the stationary cylinder and thence to the pipes 52 leading to the air boxes 10 and to the spacing pins 42 of the spacing mechanism to operate the gag-blocks and the spacing pins 42 as the case may be.

Although the operation of the paper tower is automatically controlled through the paper tower cam 46 the paper sheet 53 may be advanced by hand by lifting the lever 77 after it has been disengaged from the link 74 and the pawl 61 may then be lifted out of engagement with the ratchet wheel 60 and held in this position by a dog 93 which is adapted to engage a shoulder 94 of the pawl 61 to hold it against a stop 95.

The paper tower is operated through the bell crank 49 in the following manner. The position of the paper tower as illustrated in Fig. 7 represents the period of punching of

the material with air pressure on the gag blocks 7 and the air pins 42. During the period of shifting the paper sheet 53 as actuated by the cam 46, reverse action of the lever 49 will slack up on the link 74. The lever 77 will be lifted by action of the spring 80. The valve stems 83 and 84 will close, shutting off air pressure to the pilot valves and air pins 100 and 42 respectively. Further motion will lift air clamp bar 88 off the cylinder 50 exhausting pilot valves 100 and air pin 42 permitting them to return by spring pressure. During this period the spring 69 is under compression and when closed the link 66 will bottom in lever end 67 and further swinging of the lever 49 will take the pawl 61 off the ratchet wheel 60 bringing the pawl against the stop 95. Further movement of the lever 67 will swing the whole system until the lever 63 strikes on stop 64. This is the exact position of the system for the pawl 61 to engage the next tooth of the ratchet wheel 60. During this period the pin 72 moves freely in slot 73. Forward movement of the lever 49 operates to seat pawl 61 on the ratchet wheel 60. Further movement of the lever 49 will swing the system until the lever 63 strikes on the stop 65 taking the ratchet wheel 60 with it thus bringing the paper sheet 53 to a new position. During this period the pin 72 contacts in the lower end of slot 73. Further movement will force down the lever 77 bringing the clamp bar 88 down on cylinder 50. The valves 85 and 86 will be opened successively in the manner previously explained and air pressure is again on pilot valves and air pins 100 and 42. The valve cycle is explained in detail in relation to the operation of the eccentric in connection with Fig. 12. During the last period the spring 69 is compressed and the paper tower is again at the starting point which is the position shown in Fig. 7.

Referring to Fig. 8 the air boxes comprise a plurality of pilot valves 100 biased by coil springs 101, the valves closing the openings of pipes 52 leading from the stationary cylinder 50 of the paper tower. Associated with the pilot valves are operating valves 102 and exhaust valves 103 which respectively communicate with an air passage 104 leading to the pipes 9 of the gag block cylinders 5. The pilot valves 100 are pivoted to levers 105 that are centrally pivoted at 106 and provided with curved faces 107 that engage the stems of the valves 102 and 103 so that for a certain position of the pilot valve 100, caused by air pressure passing through the paper tower, the operating valve 102 will be opened and the exhaust valve 103 closed whereby air pressure is communicated to the gag-blocks 7 and when the pressure in the pipes 52 leading from the paper tower is released coil springs 101 will return the pilot valves to their closed position in which position the lever 105 will permit the operating valve 102 to close and

open the exhaust valve 103 thereby establishing communication of the gag-block cylinders 5 with the atmosphere in which case the punches 4 will be free to slide vertically in their sockets. There is a pilot, an operating and an exhaust valve for each gag-block cylinder so that they are separately controlled by their corresponding orifices in the paper tower which is opened to a source of air pressure by orifices occurring in the paper sheet passing through the paper tower.

The operation of the paper tower will be more readily understood in connection with the diagrams shown in Figs. 9 to 13 inclusive. Figs. 9 and 10 are diagrams graphically illustrating the operation of the reciprocating punch bar and the paper tower for rendering the gags and spacing pins operative in the manner of their function in the cam driven type of machine described in the patent referred to above, and Figs. 11, 12 and 13 illustrate the operating characteristics of the eccentrically driven punch bar and the new paper tower mechanism in accordance with the present invention.

In Fig. 9 the line A designates the operating cycle of the cam operated punch bar which has a gradually and uniformly descending stroke beginning with zero to approximately 130°, the lines *a* representing the thickness of the material to be punched or acted upon by the punches which engage the material at 75° and come through at 115° of the operating cycle. From 125° to 185° the punch bar retrieves and then there is a long dwell from 185° to 360° which latter is the starting point of the downward movement of the punch bar.

In Fig. 10 the line B graphically illustrates the action of the paper tower cam to shift the paper sheet in the paper tower and operate the gags and air pins for the punches and spacing mechanism respectively during the idle period of the punch bar. The cam is designed to render the paper tower mechanism inoperative during 230° of its rotation and operative in the following manner during the remaining 130°. The cam follower as shown in Fig. 10 is at the zero position of the cam and the straight portion of the line B beginning with zero to 180° designates the plain cylindrical surface of the cam which is the period during which the punch bar is operative in acting upon the material, the follower when passing over the remaining portion of the cam will function to operate the paper tower mechanism so that the paper is shifted at 225° and continues to move through the paper tower during the subsequent rotation of the cam up to 310°, at which time the air pressure is on to simultaneously operate the gags and the air pins of the spacing mechanism.

As shown in Figs. 9 and 10 the functions of the punch bar operating cam and the paper

tower operating cam are coordinated so that the paper tower mechanism is inoperative during the working portion of the operating cycle of the punch bar cam and the latter is out of operating contact with the punch bar during the operation of the paper tower mechanism which is the period in which the gag-blocks and spacing pins are actuated by air pressure to properly space the work with respect to the punches and dies and to effect the proper coaction between the gags and the punches which are to be effective in the next down stroke of the punch bar.

In Figs. 11 and 12 line C graphically illustrates the operating cycle of the eccentric that operates the punch bar, and as shown this line is a perfect sine curve which represents a uniform reciprocatory movement of the punch bar. The line D in Fig. 12 graphically illustrates the cam function as in Fig. 10 and is similar to line B of Fig. 10, excepting that the gag and spacing pin operations are separated, the air pressure being applied to the gags at 290° of rotation of the cam and subsequently to the air pins at 340° of rotation, so that independent sources of air pressure render the gag blocks and the spacing pins operative at 290° and 340° respectively at which points on the cam the stops 82 and 82^a Figs. 2, 6 and 7 adjusted in the manner previously explained successively contact with valve stems 83 and 84 to open the valves 85 and 86 of the paper tower, where in the old form of cam drive air pressure was simultaneously applied to the gags and spacing pins at 310° through a single valve. In the new type of paper tower and control or regulating cam the longest possible period of time is available for the operation of the gag blocks and a relatively short period of time for the operation of the spacing pins which is desirable and necessary on account of the continuous motion of the punch bar as effected by the eccentric drive over that of the early cam drive in which there was a long dwell.

In Fig. 13 the line E graphically illustrates the opening and closing of the tongs which control the position of the block 23 in the slot 24 of the swing frame, the movement of which determines the throw of the ratchet pawl 20 that engages the ratchet wheel of the feed shaft and comparing the line E with line D of Fig. 12 it will be seen that there is no interference in the operation of the spacing pins in bringing them in the line of travel of the jaws 36 and 37 on the tongs 38 and 39. Beginning at zero the gradual drop of the line E for 180° designates the closing of the tongs 38 and 39 which sets the new spacing which is subsequently effected through the ratcheting mechanism on the feed shaft 18 and from 180° to 360° the tongs are opening and the spacing pawls of the ratchet wheels are advancing to space the ma- 125

terial. At 340°, as indicated in Fig. 12, the air pressure from the paper tower mechanism forces the spacing pins 42 downwardly in the path of travel of the jaws 36 and 37 and as this is the wide open position of the tongs 38 and 39 no interference will be met with by the pins 42.

5 The conduits or pipes leading from the paper tower to the punch gags are of considerable length being twenty feet or over 10 and a sufficient lapse of time is necessary in the operation of the gags to permit air pressure passing from the tower to the gags long before the spacing pins need to be actuated.

15 It is evident from the foregoing description of this invention that the improvements disclosed therein permit the adaptation of the paper tower mechanism for controlling the punches and the spacing of the materials 20 to the eccentric driven type of punching presses, and it is further evident that the present invention provides a positive and efficient control and regulation of the punch and material spacing operations.

25 It is further obvious that variations may be made in the arrangement of the several cooperating parts of the paper tower, spacing mechanism and the punch mechanism without departing from the principles herein 30 set forth.

We claim:

1. In a multiple punch the combination of 35 a reciprocating punch bar, a die block in operative alignment therewith, a carrier for moving the work over said die block, a plurality of punches mounted on said punch bar, a spacing mechanism for intermittently actuating said work carrier, means for automatically rendering some of said punches 40 operative, and means independent of said first named means for automatically regulating said work carrier spacing mechanism.

2. In a multiple punch the combination of 45 a reciprocating punch bar, having a plurality of punches movably mounted in spaced relation and in alignment with corresponding die members, a carrier for moving the work between said punches and die members, means for automatically rendering certain 50 of said punches operative in said punch bar to act upon the work, and means for automatically changing the relative position of the work and punches, said means being independent of each other.

55 3. In a multiple punch the combination of a reciprocating punch bar having a plurality of punches movably mounted in spaced relation and in alignment with corresponding die members, a carrier for moving the 60 work between said punches and die members, means for automatically rendering certain of said punches operative in said punch bar to act upon the work, means for automatically changing the relative position of the 65 work and punches, and means for regulat-

ing the punch and work controlling means to be successively operative in the order named during predetermined intervals of the punch bar operating cycle.

4. In a multiple punch the combination of 70 a reciprocating punch bar having a plurality of punches movably mounted in spaced relation and in alignment with corresponding die members, a plurality of gag blocks corresponding to the movable punches adapted 75 to be movable in and out of alignment with the punches, a carrier for moving the work between the said punches and die members, spacing mechanism for actuating said carrier, fluid pressure means for moving the gag 80 blocks in alignment with certain of said punches and for controlling the spacing mechanism to change the relative position of the work and punches, and means for regulating the pressure acting upon the gag 85 blocks and the spacing mechanism to render them severally operative during predetermined intervals of the punch bar operating cycle.

5. In a multiple punch the combination of 90 a reciprocating punch bar having a plurality of punches movably mounted in spaced relation and in alignment with corresponding die members, a carrier for moving the work between said punches and die members, gag 95 blocks adapted to be movable in and out of alignment with said punches, a spacing mechanism for actuating the carrier, a paper tower mechanism for regulating the function of the gag blocks and spacing mechanism through independent sources of fluid pressure, and means for regulating the operation of the paper tower mechanism to render the same operative during predetermined intervals of the punch bar operating 100 cycle.

6. In a multiple punch the combination of 105 a reciprocating punch bar having a plurality of punches movably mounted in spaced relation and in alignment with corresponding die members, a carrier for moving the work between said punches and die members, gag blocks adapted to be movable in and out of alignment with said punches, a spacing mechanism for actuating the carrier, a paper 110 tower mechanism for regulating the function of the gag blocks and spacing mechanism through independent sources of fluid pressure, and a cam operated regulating device 115 operatively connected to said paper tower to regulate the pressure transmitted to the gag blocks and spacing mechanisms so as to apply it during certain predetermined intervals of the punch bar operating cycle.

7. In a multiple punch the combination of 120 a reciprocating punch bar having a plurality of punches movably mounted in spaced relation and in alignment with corresponding die members, a carrier for moving the work between said punches and die members, gag 125

- blocks adapted to be movable in and out of alignment with said punches, a spacing mechanism for actuating the carrier, a paper tower mechanism for regulating the function 5 of the gag blocks and spacing mechanism through independent sources of fluid pressure, and a cam operated regulating device operatively connected to said paper tower to regulate the pressure transmitted to the gag 10 blocks and spacing mechanism so as to apply it during certain predetermined intervals of the punch bar operating cycle, said cam actuated device being operatively connected to the punch bar operating mechanism to provide 15 a positive connection between the punch bar driving mechanism and the punch and work actuating mechanisms.
8. In a multiple punch the combination of a reciprocating punch bar having a plurality 20 of punches movably mounted and in alignment with corresponding die members, a carrier moving the work between said punches and die members, gag blocks adapted to be movable in and out of alignment with the punches, a spacing mechanism for actuating 25 said work carrier, spacing pins cooperating with said spacing mechanism to regulate the amount the work is moved, a paper tower mechanism provided with means for communicating independent sources of fluid pressure to said gag blocks and to said spacing 30

mechanism and a paper tower regulating cam for controlling the application of the pressure to the gag blocks or spacing pins during certain predetermined intervals of 35 the punch bar operating cycle.

9. In a multiple punch the combination of a reciprocating punch bar having a plurality of punches movably mounted and in alignment with corresponding die members, a carrier moving the work between said punches and die members, gag blocks adapted to be movable in and out of alignment with the punches, a spacing mechanism for actuating 40 said work carrier, spacing pins cooperating with said spacing mechanism to regulate the amount the work is moved, a paper tower mechanism provided with means for communicating independent sources of fluid pressure to said gag blocks and to said spacing 45 mechanism, and a paper tower regulating cam for rendering the paper tower mechanism operative to direct pressure to the gag blocks and subsequently and independently direct pressure to the spacing mechanism at 50 certain predetermined intervals of the operating cycle.

In testimony whereof, we hereunto sign our names.

LARS H. VOLD.

KARL R. HAMMERSTROM.
